UNITED STATES PATENT OFFICE.

GEORGE H. POOR, OF ST. LOUIS, MISSOURI, ASSIGNOR TO THE AMERICAN BRAKE COMPANY, OF SAME PLACE.

GOVERNOR FOR AUTOMATIC BRAKES.

SPECIFICATION forming part of Letters Patent No. 317,572, dated May 12, 1885.

Application filed October 13, 1884. (No model.)

To all whom it may concern:

Be it known that I, GEORGE H. POOR, a citizen of the United States, residing at St. Louis, in the State of Missouri, have invented 5 certain new and useful Improvements in Centrifugal Governors for Automatic Car-Brakes; and I hereby declare the following to be a full, clear, and exact description of the same, reference being had to the accompanying drawings, in which—

Figure 1 is a side elevation of the governor and part of the axle to which it is secured. Fig. 2 is a view at right angles to Fig. 1. Fig. 3 is an end view of the same. Fig. 4 is a detached view of the collar which clamps or is attached to the axle. Fig. 5 is a similar view of the sliding collar or disk. Fig. 6 is an enlarged view of the end of one of the bolts, which carries the springs and the locking-pin, showing the means for changing the power of the spring which operates the centrifugal arms or blocks of the governor. Fig. 7 is a sectional view of a portion of the clamp-collar, the springs, and the centrifugal arm or block. 20 Fig. 8 is a detached perspective view of the bolt-pin; and Fig. 9 is a sectional view of the bolt.

Like letters refer to like parts wherever they occur.

30 My invention relates to the construction of that class of centrifugal governors which are attached to car-axes for controlling the mechanism employed for automatically applying car-brakes, such as is shown in the patents of Lefevre and Dorre, No. 101,280, March 29, 1870; Card and Randolph, No. 231,535, August 24, 1880; Randolph, No. 241,156, May 10, 1881; Randolph, No. 241,510, May 17, 1881; Poor, No. 300,122, and many others of like general 40 character.

The main objects of the present invention are to produce a governor which can be adjusted to operate at any desired speed; to provide means for increasing the power of the 45 springs of the centrifugal arms at will, or when the spring has become weakened from any cause, and generally to simplify the construction of this class of governors. To obtain these objects I prefer to employ a flat 50 spring, coiled spirally and concentrically about

a rotatable bolt or shaft, to which one end of the spring is attached, while the opposite end of the spring is secured to the weighted arm of the governor. I also prefer to cast this bolt hollow and malleableize the same, so as to obtain lightness and strength, as well as to reduce the cost of manufacture, and though a ratchet and dog may be used with the rotatable shaft or bolt, I prefer a pin and ratchet-lugs, as will hereinafter more fully appear. 60

I will now proceed to describe my invention more fully, so that others skilled in the art to which it appertains may apply the same.

In the drawings, A indicates the shaft or car-axe to which the governor is attached. 65 The main elements composing the governor are a clamp-collar, B, secured to the axle or shaft and revolving therewith, weighted centrifugal arms C, which are separated by centrifugal force; a sliding disk or collar, D, actuated by the weighted arms C, and tension-springs E, which resist the outward movement of the weighted arms and close the same against the shaft or axle A when not overcome by centrifugal force. 70

The clamp-collar B is composed of sections b, preferably semicircular, which are held together around the axle by bolts b', so as to securely clamp the axle and rotate therewith. At diametrically-opposite points on the collar 80 B are two pairs of projecting ears, b'', between which are pivoted weighted centrifugal arms C. The weighted centrifugal arm C is preferably bifurcated at the end which is pivoted to the collar, as at c, to form a chamber to receive 85 and protect the spring E, and at its opposite end is provided with laterally-projecting pins or lugs c', which engage in cam-slots on the sliding disk or collar D.

D indicates the disk or sliding collar, which 90 is connected directly to and actuated by the weighted centrifugal arms C. The sliding disk D is preferably made of two semicircular sections adapted to encircle the axle, and has on the side next to the clamp-collar B, at half-circle distances from each other, two slotted jawed projections, d, the slots d' being curved and of such length as to permit the outer ends of the weighted centrifugal arms C to recede 95 from the axle such distance as to draw the disk 100

D toward the collar as far as may be required; In these slots d' the lateral pins or lugs c' of the weighted arms engage, and the length of the slots should not be such as to allow of excessive tension being put on the springs E.

E indicates tension-springs, by means of which the outward throw of the weighted arms is resisted, and by means of which said arms are forced against the shaft when the centrifugal force is diminished or ceases. It is evident that if the power of these devices (springs or equivalent) can be increased or diminished at will, accordingly will the governor operate at a greater or less speed of the axle or shaft.

15 To accomplish this I provide means for increasing or diminishing the power of the spring as follows: I employ a flat spring, and coil the same spirally and concentrically, securing one end thereof to the shaft or bolt F, and the other to the weighted arm C. The bolt or shaft attachment may be made by means of a lug or projection, f' , on the shaft, and a slot in the shaft end of the spring, which is the preferable manner, as it facilitates the replacing of

20 an old or useless spring, and the attachment of the opposite end may be made by means of a cross-pin, e, which passes through an eye on the end of the spring and bears on the bifurcated arms of the weighted arm C. These forms of construction are herein shown and described, not for purposes of limitation, as any means of attaching the spring may be employed, but because I have found them in practice the most desirable.

25 F indicates the bolt or shaft on which the centrifugal or weighted arm C is pivoted, and to which one end of the tension-spring E is secured. These bolts I cast hollow and malleableize, so as to obtain strength, lightness, and saving in the cost of manufacture. Each bolt has at one end a head adapted to receive a wrench, g, by means of which the bolt can be turned, in the opposite end a hole, g' , for the reception of the pin which holds the bolt 30 or shaft in place, and at an intermediate point a pin or lug, f' , for securing the end of spring E.

H (see Fig. 8) indicates the pin for holding the bolt in place. This pin has a shoulder or 35 projection, h , for retaining the pin in position, which shoulder is cut away at one or more points, h' , to permit the insertion and withdrawal of the pin. On one of the projecting ears b' of clamp-collar B, on which the 40 weighted arm C is pivoted, and surrounding the shaft or bolt-hole, are arranged a series of projections or lugs, h^2 , with one or more of which lugs the locking-pin H engages accordingly as the bolt is turned. It will be noted 45 that this pin H, in addition to its function as a key, acts as a dog or pawl, while the lugs h^2 perform the office of a ratchet; and therefore a pawl-and-ratchet mechanism could be substituted therefor, though it would be retrograde in the art.

The mechanism interposed between the governor and the draw-bar on which actuates the

brakes is not shown or described, as it forms no part of the present invention. It may be of the character shown in any of the patents 70 hereinbefore referred to, or of any character which will answer the purpose.

The devices being of substantially the general character hereinbefore specified will operate as follows: When the train is at rest or 75 moving at a low rate of speed, and the centrifugal force is too low to overcome the springs E, the weighted centrifugal arms C will be held against the axle by said springs; but when the speed of the train is such that the centrifugal force overcomes the springs E, the weighted arms C will separate and the pins c' , moving outward along the slots d' , will draw the sliding disk or collar D toward the fixed collar B until the outward movement of the 80 arms is arrested by the pins c' reaching the outer ends of slots d' .

It is evident that the movement of the sliding collar and the tension put on the springs can be limited by the length of slots d' .

If the springs E become weak from use, or if the tension thereof or their resistance to the centrifugal force is to be increased, a wrench is placed on the head of the bolt F, the pin H is withdrawn, and the bolt F rotated to close 90 the coils of the spring E, after which the pin H is inserted, and a slight reaction of the spring will carry the pin against one of the lugs h^2 and its shoulder h under the lug, so that the pin H cannot escape.

100 The advantages of my invention are, first, the ability to set the governor so as to determine the speed required to operate the governor and apply the brakes; second, the ability to increase the force of the tension-spring 105 at will to compensate for loss of power from use, &c.; third, the facility of repair without removal and by unskilled labor in case of injury to the tension-springs; and, finally, the great simplicity and durability of the structure, 110 a feature of great importance in this class of mechanism.

Having thus described the nature, operation, and advantages of my invention, what I claim, and desire to secure by Letters Patent, 115 is—

1. In a centrifugal governor, the combination, with the centrifugal arm, of an adjustable tension-spring, substantially as and for the purposes specified.

2. In a centrifugal governor, the combination, with the centrifugal arm, of a concentrically-coiled tension-spring, and a rotatable bolt or shaft, to which one end of the tension-spring is attached, substantially as and for the purposes specified.

3. In a centrifugal governor, the combination of a centrifugal arm, a coiled tension-spring secured at one end to the centrifugal arm, a rotatable bolt or shaft to which the 130 opposite end of the tension-spring is secured, and a pawl-and-ratchet mechanism for securing the rotatable bolt, substantially as and for the purposes specified.

4. In a centrifugal governor, the combination of the bifurcated centrifugal arm, the concentrically-coiled tension-spring arranged in the bifurcation of the centrifugal arm, the 5 cross-pin for securing the spring to the arm, and the pivot-bolt having a lug or projection for securing the opposite end of the tension-spring, substantially as and for the purposes specified.
- 10 5. In a centrifugal governor, the combination, with a centrifugal arm, a coiled tension-spring, and a pivot-bolt to which the tension-spring is secured, of the shouldered pin for

securing the pivot-bolt and the series of lugs arranged around the bearing of the pivot-bolt, 15 substantially as and for the purposes specified.

6. The hollow cast malleableized pivot-bolt for the centrifugal arm of the governor, substantially as and for the purposes specified.

In testimony whereof I affix my signature, in 20 presence of two witnesses, this 29th day of September, 1884.

GEORGE H. POOR.
